UNITED STATES PATENT OFFICE

THOMAS CHARLES BROMLEY, OF LEICESTER, ENGLAND, ASSIGNOR TO JACQUARD
KNITTING MACHINE COMPANY, INC., OF PHILADELPHIA, PENNSYLVANIA, A COR-
PORATION OF NEW YORK

CIRCULAR KNITTING MACHINE

Application filed September 27, 1926, Serial No. 137,987, and in Great Britain October 1, 1925. Renewed
September 16, 1931.

This invention relates to circular knitting machines and has reference to machines of this kind furnished with jacquard mechanism adapted to control the action of the needles for producing pattern effects in the knitted fabric.

The object of the invention is to provide in or for a circular knitting machine of the type having slidable needles, an improved form of jacquard mechanism, the main features of improvement comprising, simplicity and cheapness of construction, certainty in action, capability of ready adaptation to produce variation in the action for obtaining pattern effects, individual needle control and an arrangement by which the wear upon the jacquard member, due to the engagement and disengagement of the feelers therewith and therefrom is reduced to a minimum.

The last mentioned feature of improvement is an important one where, as is mainly intended in the present case, jacquard members of paper or similar thin material are employed as it prolongs the useful life of such members.

The feature of individual needle control is also important since by being able to control each needle of the machine separately and independently by the jacquard the pattern can be varied to a greater extent than is the case where two or more needles are controlled together.

The invention therefore consists of jacquard mechanism which includes a racking drum or cylinder carrying the pattern member, a series of feelers mechanically brought into and out of contact with the pattern member, a series of selectors for actuating the needles, and connecting means between the feelers and selectors such that movement is imparted to the selected needles by the selectors actuated by the drum.

According to the preferred arrangement the whole of the requisite movement of the selected needles is imparted entirely by the

selectors. For instance, if the selected needles are to be raised to clearing height whilst the other needles not selected remain down and miss the yarn, they are raised to the desired height by the selectors.

The invention includes as a modification an arrangement wherein there is provided in addition to the parts aforesaid a cam whereby, following initial movement of the selected selectors by racking drum or cylinder to bring them into the path of the cam said selectors are further actuated so as to complete the operation of the corresponding needles. In this arrangement the selected needles are therefore actuated partly by the selectors, feelers and racking drum and partly by the cam operating through the medium of the selectors.

In each of the aforesaid arrangements the drum or cylinder carrying the pattern member is longitudinally grooved and as the pattern member, which may consist of a paper or other band, passes over the drum the transverse rows of holes in said member come into register with the grooves. When the feelers are moved into contact with the pattern member those which are allowed by the holes to pass through said member drop into the groove, and upon the cylinder being racked on, are drawn forward by the latter so that through the intermediate connections, the corresponding selectors are actuated to bring about the operation the corresponding needles in the desired manner as will be described later herein. Since the feelers which pass through the pattern member are subsequently moved by the grooved drum or cylinder, the said member is not called upon to do this work, its sole duty being to prevent certain of the feelers from engaging with the grooved drum. A cam is provided for restoring the selected selectors and corresponding feelers to the normal position subsequently to their action as aforesaid.

Further the feelers conveniently consist

of levers which are mounted to be capable of sliding as well as pivotal movement. Each feeler has a nose for contact with the pattern member and engagement with the grooved drum and is spring-controlled in such a way that the nose is induced to maintain contact with the drum except when all the feelers are positively moved away from said drum by mechanical means as will be described presently.

Each feeler lever is connected by a pivoted link or equivalent device with a selector which is in the form of a bell-crank lever so disposed that while one limb to which the connecting link is attached is acted upon by the cam or cams (according to the arrangement employed) the other limb serves to raise the corresponding needle in the needle cylinder of the machine either directly or through the medium of a jack.

The feelers are moved pivotally away from the grooved drum by a reciprocating or oscillating member such as a bar which receives its motion by cam actuated mechanism.

In order that the invention may be more clearly and readily understood arrangements constituting practical examples of the same designed for application to a circular latch needle knitting machine of the stationary needle cylinder type will now be described with reference to the accompanying drawings wherein:—

Figure 1 is a sectional side elevation of an arrangement wherein the selectors are actuated wholly by the feelers and racking drum for imparting the desired movement to the selected needles.

Figure 2 is a diagrammatic representation of the operative relationship between cams employed in said arrangement.

Figure 3 is a detail view of a cam for restoring the selectors to normal position.

Figure 4 is a plan showing one manner of connecting the selectors with their operating links.

Figure 5 is a sectional plan taken on line V—V of Figure 1.

Figure 6 is a diagrammatic plan illustrating the disposition of a plurality of jacquard units round the machine.

Figure 7 is a sectional side elevation of a modification of the arrangement shown in Figure 1, and,

Figure 8 is a diagrammatic representation of the operative relationship between cams employed in the modified arrangement.

Referring to Figure 1, there is provided for each needle 1 in the cylinder 2 a pivoted selector 3, a pivotal and sliding feeler 4 and a connection consisting of a link 5 between these two parts. The selectors which are of bell crank form are each disposed vertically and radially or substantially radially with one limb 3a extending horizontally into the corresponding needle trick 6 and acting against

a butt 7 on the lower end of a jack 8 associated with the needle, and the other limb 3b standing up adjacent to but normally clear of the circular track of a cam 9 (see also Figure 3) attached to and rotating with a circular carrier plate 10 rotating with the cam box 11 of the machine.

The selectors are mounted in a tricked bed 12 located in the machine bed 13 and are each pivoted independently of the others by means of a pin 14 which rests in grooves or recesses 15 cut in the sides of the tricks.

The feelers are carried by a grooved block 16 mounted on a bracket 17 in turn attached to the machine bed 13, which bracket also supports a rotatable jacquard drum 18 provided with grooves a few of which are shown at 19. Each feeler has a slot 20 therein so that in addition to turning on the pivot pin 21 in the block it can also slide to and fro. Between the inner end of the feeler and the upstanding limb of the corresponding selector is the connecting link 5 pivotally attached to the parts in a suitable manner. At the outer end the feeler has formed upon it a downwardly extending nose 4a for engagement with the grooved jacquard drum situated thereunder, and at the inner end it is formed with a hook 4b to which is connected a spring 22 attached to a lug on the block 16 whereby the feeler is drawn upwards, the effect of which is to press the nose 4a downwards upon the pattern band member 23 and drum.

Carried by links 24 pivoted at 25 on the bracket 16 is a lifter bar 26 arranged transversely under the feelers this bar being lifted up and down by a lever 27 to one end of which the links 24 are connected and which is fulcrumed at 28 on a support 29, attached to a fixed ring 30 in which the cam carrier plate 10 revolves. The opposite end of the lever is located in the circular path of a cam 31 mounted on the plate 10.

The jacquard drum is racked round by means of a cam 32 mounted to revolve in a carrier ring 33 suitably attached to the lower part of the machine frame, said cam imparting movement to a lever 34 fulcrumed at 35 on a bracket 36 attached to the ring 33 which lever by means of a coupling link 36 actuates a suitable racking device (a part 38 of which is shown attached to the link 37) associated with the drum. The lever 34 is fitted with a roller 39 for engagement by the cam.

The operation of the mechanism will now be described with the aid of Figure 2 which as hereinbefore mentioned represents diagrammatically the operative relation of the various cams hereinbefore referred to. Normally the feelers are pulled down by their springs so that their noses rest upon the imperforate portions of the jacquard band as represented by full lines in Figure 1, or pass through holes therein into the corresponding

groove in the drum as the case may be. The racking movement of the drum then commences that is to say the cam 32 engages the roller 39 and by means of the rise 32a (Figure 5 2) lifts the lever 34 and the coupling link and rocks the drum round in the direction of the arrow *a* (Figure 1) so that those feelers whose noses have passed through the jacquard are drawn forward by the grooved drum, as represented by dot and dash lines *b* while the other feelers are left behind, the feelers thus moved turning the corresponding selectors on their pivots as represented at *c* so that the horizontal limbs thereof raise the corresponding needles to the clearing position represented at *d*. At this stage the drum is allowed to pause by reason of a dwell 32b on the racking cam while the cam 31 engages and actuates the lifter lever 27 so that all the 10 feeler levers are lifted clear of the jacquard band and drum by the lifter bar 26 after the selected selectors have been actuated and before the selected feelers return to normal position, in order to obviate wear and tear of the jacquard band. After actuation of the feelers in this manner and while they are held raised a further rise 32c on the racking cam completes the movement of the drum to bring a fresh portion of the jacquard and another groove under the feelers, and just before the completion of this movement the cam 31 releases the lever 26 so that the lifter bar falls and allows the feelers to be pulled down again by their springs. Immediately 20 after the feelers are raised and before they are lowered as aforesaid the cam 9 restores the selected selectors to normal position by acting on the vertical limbs thereof, as represented in Figure 3, and consequently the 25 feelers are brought into line again ready for further selection. The cam 32 subsequently allows the lever and coupling rod to fall in readiness for the next operation of the drum. The feeler noses are therefore disengaged 30 from the jacquard band and drum while the latter are stationary following their initial movement thereby obviating the tendency there might otherwise be on the part of the noses to drag on the band, and during the 35 return movement of the feelers over the band they are held clear of the band thereby preventing undue wear.

The selected needles are caused to knit in the usual manner immediately after the restoration of the selectors to the normal position.

It is found convenient to construct the connecting links so that they fit within the spaces 40 between adjacent selectors as shown in Figure 4 and to provide them with fixed pins or studs 40 which fit into holes in the selectors, the link connected to one selector being thus kept in place by the next adjacent selector. 45 Said links may be similarly attached to the

feelers. Any other suitable construction may be adopted.

In order to enable a self-colour, plain or non-patterned fabric to be made means are provided to enable the jacquard mechanism to be put out of action. These means may take any suitable form and be arranged to act, preferably automatically under pattern control, upon some convenient part. Preferably a catch or detent is movable into and out of position for stopping the action of the racking lever of the jacquard drum.

In a concrete example illustrated in Figures 1 and 5 a catch 41 capable of yielding pivotally, if necessary against the action of a spring 42 is mounted upon an oscillatory ring 43 controlled by pattern mechanism (not shown) of the usual type and adapted to be moved into position under a lug 44 on the coupling link 37 which operates the racking means of the drum so as to hold lever 34 connected thereto from engagement with its cam. Normally the catch 41 occupies the position shown by full lines in Figure 5. When the ring 43 is moved in the direction of the arrow *x* the catch is brought into line with the lug 44 as represented by dot and dash line *e* so that when the coupling link, next rises the lug 44 first engages the catch and causes it to yield against the action of its spring, and then releases it so that it is moved under the lug and thereby holds the coupling rod and consequently the lever 34 in the raised position.

The complete jacquard mechanism for the machine may comprise several units each of which includes, a jacquard drum and band, a series of feelers and corresponding selectors, mechanism for racking the drum and lifting the feelers and means for putting the racking out of action. The units are disposed at intervals around the machine as represented diagrammatically in Figure 6 the series of feelers and selectors in each serving for corresponding needles. The needles selected by each unit are actuated simultaneously by the racking drum but the racking drums of the units are actuated in succession as the actuating cam revolves.

The pattern effects may be produced by known needle actions which actions are brought about by the jacquard mechanism.

While it is convenient in the matter of construction to employ connecting means such as pivoted links between the feelers and selectors, we may dispense with such means and connect the feelers directly to the selectors in a suitable manner.

As regards the modification hereinbefore referred to and now to be described with reference to Figures 7 and 8 the construction arrangement and operation of the essential parts is practically the same as that described with reference to Figure 1 so that in Figure 7 only so much of the mechanism as is neces-

sary to enable the modification to be understood is shown. The difference between the two arrangements is that in addition to the other parts of the mechanism a cam 45 which is attached to the cam carrier plate 10 so as to miss the vertical limbs 3b of the selector 3, when the latter are in normal position, as the said plate revolves. Further the racking cam 32d (Figure 8) is designed so that the first rise 32e thereof operates the racking drum only to such extent as to move the selected selectors into the circular path of the cam 45 i. e. into the position *g*, during which movement the horizontal limb 3a each of said 50 selectors raises the corresponding needle 1 from the low position shown by full lines to the intermediate e. g. tucking position *h*. During a pause in the movement of the drum due to the dwell 32f the cam 45 operates the selected selectors so that they are moved to position *j* and the needles thereby raised to the high e. g. clearing position *l*. The grooves in the jacquard drum and the holes in the jacquard band are made large enough to permit of the slight endwise movement of the feelers due to the action of the said cam. The further operation of the mechanism is now similar to that previously described herein. That is to say while the drum pauses the lifter cam 31 comes into action to raise the feelers clear of the drum and band and while the feelers are held raised a further rise 32g on the racking cam completes the operation of the drum to bring a fresh series of holes and another groove into position, the cam 9 restores the selectors to normal position and consequently brings the feelers into line again, and just before the drum completes its movement the cam 31 releases the lever 27 to allow 55 the feelers to be pulled down again by their springs.

Thus the selectors which impart the necessary movement to the selected needles are actuated partly by the feelers and racking drum and partly by the cam 45, the needles selected by each unit being moved simultaneously by the racking drum, but successively by the cam.

As in the previous arrangement the selected needles are caused to knit immediately after the action of the cam 9.

In each of the arrangements herein described there may be as many sets of operating cams as there are jacquard units or there may be more jacquard units than sets of cams. For example, in a four feeder machine employing eight jacquard units there may be four sets of cams so disposed that while said units are operated in succession by each set four alternate units are operated simultaneously while the other four are idle.

What I claim then is:—

1. In a circular knitting machine having slideable needles, jacquard mechanism for effecting actuation of individual needles for

patterning purposes, comprising in combination, a racking drum, a jacquard member carried by said drum, a series of feelers between which and with the jacquard member there is relative to and fro movement whereby feelers are selected to engage the drum, and a series of needles engaging selectors coupled to the feelers so that upon rotary movement of the racking drum the force exerted thereby on the selected feelers is applied directly to the corresponding needles to move the latter and determine the function thereof. 70

2. In a circular knitting machine having slideable needles, jacquard mechanism for effecting actuation of individual needles for patterning purposes comprising, in combination, a racking drum, a jacquard member carried by said drum, a series of feelers movable into and out of contact with the jacquard member whereby feelers are selected to engage the drum, when required, so as to be actuated thereby, means for effecting said movement of the feelers, a series of needle engaging selectors coupled to the feelers so that upon rotation of the racking drum the force exerted thereby upon the selected feelers is applied directly to the corresponding needles to move same and determine the function thereof and a cam for restoring the selected 80

selectors and feelers to their original position subsequently to their actuation by the drum. 90

3. In a circular knitting machine having slideable needles, jacquard mechanism for effecting actuation of individual needles for patterning purposes comprising, in combination, a longitudinally grooved racking drum, a perforated jacquard member carried by the drum, the perforations corresponding with grooves in the drum, a series of feelers adapted to contact with the jacquard member so that those which register with perforations enter the corresponding groove in the drum and are operated thereby, means for moving the feelers relatively to the jacquard member, a series of needle engaging selectors 100 coupled to the feelers, so that upon rotation of the racking drum the force exerted thereby upon the selected feelers is applied directly to the corresponding needles to move the same and determine the function thereof, 110 and a cam for restoring the selected selectors and feelers to their original position subsequently to their actuation by the drum. 105

4. In a circular knitting machine having slideable needles, jacquard mechanism for effecting actuation of individual needles for patterning purposes comprising, in combination, a racking drum, a jacquard member carried by said drum, a series of pivotal and slideable feelers adapted to contact with the jacquard member whereby feelers are selected to engage the drum when required so as to be actuated slidably thereby, an oscillatory member for engagement with the feelers, a cam for actuating said member to move the 120

- feelers pivotally away from the jacquard member, a series of needle engaging selectors coupled to the feelers so that upon rotation of the racking drum the force exerted thereby upon the selected feelers is applied directly to the corresponding needles to move same and determine the function thereof, and a cam for restoring the selected selectors and feelers to their original position subsequently to their actuation by the drum. 5
5. In a circular knitting machine having slideable needles, jacquard mechanism for effecting actuation of individual needles for patterning purposes, comprising, in combination, a racking drum, a jacquard member carried by said drum, a series of feelers movable into and out of contact with the jacquard member whereby feelers are selected to engage the drum when required, so as to be operated thereby, means for effecting said movement of the feelers, a series of pivotal needle engaging selectors connected to the feelers so that upon rotation of the racking drum the force exerted thereby upon the selected 10 feelers is applied directly to the corresponding needles to move same and determine the function thereof, and a cam for restoring the selected selectors and feelers to their original position subsequently to their actuation by the drum. 15
6. In a circular knitting machine having slideable needles, jacquard mechanism for effecting actuation of individual needles for patterning purposes, comprising, in combination, a racking drum, a jacquard member carried by said drum, a series of spring controlled pivotal and slideable feelers adapted to contact with the jacquard member whereby feelers are selected to engage the drum 20 when required so as to be actuated slideably thereby, a lifter bar disposed transversely under said feelers, pivoted links supporting the bar, a lever connected to the bar, a cam for actuating the lever to move the feelers pivotally away from the jacquard member, a series of needle engaging selectors coupled to the feelers, so that upon rotation of the racking drum the force exerted thereby upon the selected feelers is applied directly to the corresponding needles to move same and determine the function thereof, and a cam for restoring the selected selectors and feelers to their original position subsequently to their actuation by the drum. 25
7. In a circular knitting machine having slideable needles, jacquard mechanism for effecting actuation of the needles for patterning purposes, comprising in combination, a drum having longitudinal grooves therein, means for actuating the drum, a perforated jacquard member carried by the drum, the perforations corresponding with the grooves in the drum, a series of feelers adapted to contact with the jacquard member so that those which register with perforations enter the corresponding groove in the drum and are operated thereby, means for moving the feelers relatively to the jacquard member, a series of needle engaging selectors coupled to the feelers so that upon rotation of the racking drum the force exerted thereby upon the selected feelers is applied directly to the corresponding needles to move same and determine the function thereof, a cam for restoring the selected selectors and corresponding feelers to their original position subsequently to their actuation by the drum. 30
8. In a circular knitting machine having slideable needles, jacquard mechanism for effecting actuation of the needles for patterning purposes, comprising, in combination, a longitudinally grooved racking drum, a perforated jacquard member carried by the drum, the perforations corresponding with the grooves in the drum a series of spring controlled pivotal and slideable feelers adapted to contact with the jacquard member so that those which register with perforations enter the corresponding groove in the drum and are drawn forward thereby, an oscillatory member for engagement with the feelers, a cam for actuating said member to move the feelers away from the jacquard member, a series of needle engaging selectors coupled to the feelers, so that upon rotation of the racking drum the force exerted thereby upon the selected feelers is applied directly to the corresponding needles to move same and determine the function thereof and a cam for restoring the selected selectors and feelers to their original position subsequently to their actuation by the drum. 35
9. In a circular knitting machine having slideable needles, jacquard mechanism for effecting actuation of the needles for patterning purposes, comprising, in combination, a longitudinally grooved drum, a perforated jacquard member carried by said drum, the perforations corresponding with the grooves in the drum, a series of spring controlled pivotal and slideable feelers adapted to contact with the jacquard member so that those which register with the perforations enter the corresponding groove in the drum and are actuated slideably thereby, a lifter bar disposed transversely under said feelers, pivoted links supporting said bar, a lever connected to the bar, a rotary cam for acting on said lever to lift the feelers off the jacquard member, a series of needle engaging selectors coupled to the feelers, so that upon rotation of the racking drum the force exerted thereby upon the selected feelers is applied directly to the corresponding needles to move the same and determine the function thereof and a rotary cam for restoring the selected selectors and corresponding feelers to their 40

original position, subsequently to their actuation by the drum.

10. In a circular knitting machine having slideable needles, jacquard mechanism for effecting actuation of the needles for patterning purposes, comprising in combination, a longitudinally grooved racking drum, a perforated jacquard member carried by the drum, said perforations corresponding with 10 the grooves in the drum, a series of spring controlled pivotal and slideable feelers adapted to contact with the jacquard member so that those which register with perforations enter the corresponding groove in the drum 15 and are actuated slidably thereby, a lifter bar disposed transversely under said feelers, pivoted links supporting said bar, a lever connected to the bar, a rotary cam for actuating said lever to lift the feelers of the 20 jacquard member, a series of pivotal needle actuating selectors, connecting links between the feelers and selectors, so that upon rotation of the racking drum the force exerted thereby upon the selected feelers is applied directly 25 to the corresponding needles to move same and determine the function thereof, and a rotary cam for restoring the selected selectors and feelers to their operative position subsequently to the actuation by the drum.

30 11. The combination with a circular knitting machine having a circular bank of stitch-forming-elements movable for patterning purposes, of a pattern mechanism comprising a movable pattern-holding member 35 having at least one feeler-receiving recess therein, a perforated pattern carried thereby, the perforations therein corresponding with the recess or recesses in said pattern-holding member, a series of feelers to contact with 40 the pattern so that those which register with perforations enter the recess or recesses of said pattern-holding member for engagement with the latter and for movement by the latter as the latter is moved, a series of 45 selectors coupled to said feelers for actuation thereby and related to said stitch-forming-elements to actuate the same as the selectors are actuated by said feelers, and means for moving said pattern-holding member while 50 feelers extend through pattern-perforations into said recess or recesses to thereby move selected feelers, selectors and stitch-forming-elements.

55 12. The subject matter of claim 11, characterized by the fact that the last mentioned means moves the pattern-holding member to such an extent that the selected stitch-forming-elements are moved thereby the whole distance required for patterning purposes.

60 13. The subject matter of claim 11, characterized by the fact that the last mentioned means moves the pattern-holding member to such an extent that the selected stitch-forming-elements are moved thereby part of the 65 whole distance required for patterning pur-

poses, in combination with a cam revolving around the axis of the knitting machine for completing the movement of the partly-moved stitch-forming-elements.

14. The combination with a circular knitting machine having a circular bank of stitch-forming-elements movable for pattern purposes, of a pattern mechanism comprising a plurality of pattern-holding members each having at least one feeler-receiving recess therein, a perforated pattern carried by each of said members, the perforations in the patterns corresponding with the recess or recesses in the respective pattern-holding members, a series of feelers to contact with each of said patterns so that those which register with perforations enter the recess or recesses of the respective pattern-holding member for engagement with the latter and for movement by the latter as the latter is moved, 75 selectors respectively coupled to said feelers for actuation thereby and related to said stitch-forming-elements to actuate the same as the selectors are actuated by said feelers, and means for moving said pattern-holding members successively and respectively while feelers extend through pattern-perforations into the recess or recesses thereof to thereby move selected feelers, selectors and stitch-forming-elements. 80

15. The combination with a circular knitting machine having a circular bank of needles slideable for patterning purposes, of a pattern mechanism comprising a rotatable drum having a plurality of feeler-receiving recesses therein, a perforated pattern carried thereby, the perforations therein corresponding with the recesses of the drum, a series of feelers to contact with the pattern so that those which register with perforations enter the recesses of the drum for engagement by the drum and for movement by the drum as the drum is rotated, a series of selectors coupled to said feelers for actuation thereby and related to said needles to slide the latter 100 as the selectors are actuated by said feelers, and means for rotating the drum while feelers extend through pattern-perforations into the drum recesses to thereby move the selected feelers, selectors and stitch-forming-elements. 105

16. The combination with a circular knitting machine having a circular bank of stitch-forming-elements movable for patterning purposes, of a pattern mechanism comprising a movable pattern-holding member having at least one feeler-receiving recess therein, a perforated pattern carried thereby, the perforations therein corresponding with the recess or recesses of said pattern-holding member, a series of feelers to contact with the pattern so that those which register with perforations enter the recess or recesses of said pattern-holding member for engagement with the latter and for move- 110 115 120 125 130

ment by the latter as the latter is moved, a series of selectors respectively related to said feelers and related to said stitch-forming-elements to actuate the same as the selectors are actuated, a cam revolving around the axis of, the knitting machine to actuate selected selectors strictly *seriatim*, and means for moving said pattern-holding member while feelers extend through pattern-perforations into said recess or recesses to thereby move selected feelers to relate the corresponding selectors to said cam for movement thereby.

In testimony whereof I affix my signature.
THOMAS CHARLES BROMLEY.
